UNITED STATES PATENT OFFICE

2,208,297

SIGNAL APPARATUS

Julius J. Lipp, Chicago, Ill.

Application September 18, 1939, Serial No. 295,501

1 Claim. (Cl. 40—77)

This invention relates to improvements in signal apparatus and more especially such a device used for signaling the number of the down or play in football games and similar contests and sports.

5 The device is not limited to the particular use described as it will be seen that it may have a very broad applicability in connection with signaling apparatus of all kinds. As here shown, it is particularly adapted for use in connection with 10 night football to show an illuminated figure or other signal to indicate the down or play of the game.

My improved device is simple in construction and operation, light in weight, but strong and 15 rugged. It will be found that it is easy to carry the device and manipulate the same.

Other features and advantages of my invention will appear more fully as I proceed with my specification.

20 In that form of device embodying the features of my invention shown in the accompanying drawing, Fig. 1 is a view in front elevation, partly in section; Fig. 2 is a sectional view taken as indicated by the line 2 of Fig. 1, but on an enlarged scale; and Fig. 3 is a sectional view taken as indicated by the line 3 of Fig. 2.

As shown in the drawing, the device includes a post 10 which may be made of any desired length in order to bring the signal box of the 30 device to the desired height. The post is preferably pointed at the bottom as indicated by 10^a and at least the upper portion thereof is hollow. Preferably the post is made of any suitable metallic hollow tubing.

35 On the upper end of the post 10 is a rectangular signal box 11 and above that a suitable handle 12 for carrying the device.

The box 11 is hollow and provided with an electric light inside adapted to selectively illuminate 40 the figure or signal on one face of the box 11. For example, as here shown, the four sides of the box 11 may bear translucent or transparent windows having the shapes 1, 2, 3, and 4, respectively, any one of which may be illuminated to 45 designate the particular down. In general, the selectivity of the signal is obtained by means of rotating the box 11 on the rest of the device. Inside of the box 11 the source of illumination is 50 screened or shaded so that it will be directed against only one face of the box 11 at one time. Consequently, by rotating the box 11 any of its faces and consequently any of the signals 1, 2, 3, or 4 may be illuminated by the light inside.

At the upper end of the post 10 there is provided a cap or plate 13 forming the bottom of a

5 lamp chamber 14 containing a suitable electric lamp or other source of illumination 15 surrounded on three sides by the screen or reflector 16. The upper end of the lamp chamber is closed by the upper plate or disc 17 connected to the lower plate 13 by the three posts 18, 18. The discs 13 and 17 are circular and the upper disc carries the circular extension 19 in which is mounted the handle 12. The screen or reflector 16 has its edges attached to two of the rods 18 by means 10 of the clamps 20. As shown in Fig. 3, the open side of the lamp chamber lies between the posts 18, 18 to which the edges of the screen 16 are attached. This open side in Fig. 3 is indicated by 14^a.

15 The box 11 is rotatively mounted on the discs 13 and 17, the latter being flanged for this purpose as indicated by 13^a and 17^a. The upper part of the box is provided with a conical cap 11^a having a collar 11^b surrounding the lower part 20 of the handle 12 and resting on the upper edge of the tubular extension 19 on the upper disc 17.

The signal box 11 is provided at the corners with inwardly projecting diagonal baffles 21 adapted to register with the edges of the screen 25 16 so that in any one position light from the lamp box will be directed against one face only of the box 11 and screened from the three remaining faces. As here shown, the signals on the four faces of the box 11 are the numbers 30 1, 2, 3 and 4. Each of these is formed by making a suitable opening through the face of the box, and preferably placing sheet material such as translucent red glass 22 behind the face. For example, as shown in Figs. 1 and 2, the face 11^c 35 of the box 11 is provided with the openings or windows 23 and 24 to indicate the figure 4.

25 indicates a spring-pressed ball carried by the collar 11^b of the box 11 yieldingingly engaging selectively four depressions 26 in the handle 12 in 40 order to position the box 11 in one of its four positions exposing one of the four faces and the signal thereon to the light from the lamp chamber 14, depending upon how the box is positioned.

45 The lamp 15 is energized by dry cells 27, 27 carried in the hollow post 10 resting on the spring 28 which in turn is supported by the cross-bar 29 in the post 10. The lower end of the battery thus formed is grounded through the spring 28 and the upper cell has its central terminal in contact with the insulated member 30 mounted in the disc 13. 50 31 indicates the wire connecting the member 30 with the operating switch 32 on the handle 12. 33 indicates the wire leading from this switch to one 55

terminal of the lamp 15, the other terminal of which is grounded.

In operating the device, the box 11 is rotated until the desired face and consequently the desired signal is opposite the open face 14^a of the lamp chamber 14. When in this position, the lamp 15 will illuminate the signal on that face.

While I have shown and described certain embodiments of my invention, it is to be understood that it is capable of many modifications. Changes, therefore, in the construction and arrangement may be made without departing from the spirit and scope of the invention as disclosed in the appended claim, in which it is my intention 15 to claim all novelty inherent in my invention as broadly as permissible, in view of the prior art.

What I claim as new and desire to secure by Letters Patent is:

A device of the character described, including: a hollow post; a cap on the top of the post; a stationary lamp chamber on said cap, said cap forming the bottom of said lamp chamber, said lamp chamber being closed on three sides but open on the fourth side; a signal box rotatively mounted on said cap, said lamp chamber lying inside of said signal box, said signal box having a plurality of faces, each having a light transmitting signal portion adapted to be illuminated from the inside 10 of the box; an electric lamp in the lamp chamber; a battery in the hollow post for energizing the lamp in the lamp chamber; electrical connections between the battery and lamp; and a handle above the signal box.

JULIUS J. LIPP.
